IMPULSE GENERATOR

Richard C. Coupland, United States Army,
Norfolk, Va.

Application October 2, 1934, Serial No. 746,532

10 Claims. (CL 89—27)

(Granted under the act of March 3, 1883, as
amended April 30, 1928; 370 O. G. 757)

The invention described herein may be manufactured and used by or for the Government for governmental purposes, without the payment to me of any royalty thereon.

- 5 This invention relates to an impulse generator employed in a synchronized control system such as is used to control the firing of machine guns between the blades of a rotating propeller of aircraft.
- 10 The most pressing requirement in a device of this character is reliability of functioning. With this in mind the purpose of this invention is to provide an impulse generator having a single sear which may be selectively controlled by a mechanical or by an electrical operating mechanism. In order to provide a compact structure the elements of the electrical unit are contained in the housing of the impulse generator.

With the foregoing and other objects in view, the invention resides in the novel arrangement and combination of parts and in the details of construction hereinafter described and claimed, it being understood that changes in the precise embodiment of the invention herein disclosed may be made within the scope of what is claimed without departing from the spirit of the invention.

A practical embodiment of the invention is illustrated in the accompanying drawings, 20 wherein:

Fig. 1 is a view in side elevation of a gun control assembly.

Fig. 2 is a longitudinal sectional view of the impulse generator showing the sear in engagement with the cam follower.

Fig. 3 is a similar view with the sear disengaged from the follower.

Fig. 4 is a sectional view on the line 4—4 of Fig. 2.

40 Fig. 5 is a sectional view on the line 5—5 of Fig. 3.

Fig. 6 is a detail view of the cam.

Fig. 7 is a plan view partly in section showing a modification.

45 Referring to Fig. 1 the gun control assembly consists of an impulse generator A connected to a trigger motor B by means of an impulse cable and cable housing C.

The impulse generator unit (Figs. 2 and 3) 50 is arranged to constitute a compact integral part of the airplane engine synchronized thereto during or after assembly and it consists of a housing 5 in which is mounted a driven shaft 6 having a gear 7 by which it receives its energy from a driving shaft 8 of the engine. The shaft 6 is

supported by anti-friction bearings 9—9 and carries a cam 10 positioned in the lower portion of the housing 5. The shaft 6 rotates at a speed to give a cam impulse for each blade of the propeller of the airplane engine. When the shaft 6 is driven at the same speed as the propeller the cam will have the same number of lobes as there are blades on the propeller while the number of lobes will be doubled if the shaft is driven at half of the propeller speed.

5 A cam follower 11 arranged parallel to the driven or cam shaft 6 is slidably mounted in the housing 5 and has a foot 12 carrying a roller 13 adapted to engage the cam surface of the cam 10. Threaded on the other end of the follower is a 15 plug 14 in which is secured the impulse cable 15 leading to the trigger motor B. The cable is sheathed in a tube 16 which is secured in a socket 17 removably held in place by a nut 18 threaded to the housing 5.

20 Referring to Fig. 2 the cam follower is normally held immovable in a depressed position by means of a sear plunger 19 mounted in the upper part of the housing 5 and arranged to enter a recess 20 in the cam follower. In order to reduce friction the sear plunger carries a number of rollers 21—21 and the cam follower carries a roller 22 projecting into the recess 20. The sear plunger is normally urged towards the cam follower by means of a spring 23 confined between 25 the sear and the housing 5. A cable 24 attached to the sear is employed to mechanically retract the sear and thereby release the cam follower. The cable 24 is actuated by a hand lever 25 (Fig. 1) placed on the control stick 26 of the 30 airplane.

35 An electrical control unit for retracting the sear is also provided and is contained in the housing 5. This unit comprises an armature 27 and commutator 28 carried by the driven shaft 6 and 40 a magnetic field 29 carried by a casing 30 mounted on anti-friction bearings 31—31 and carrying one of the bearings 9 of the shaft 6. The field 29 is of the permanent magnetic type or as shown of the self-excited type under excitation at all 45 times so that the time lag required to build up a current flow in the closed circuit will be a minimum.

The casing 30 carries brushes 32—32 wiping the commutator 28 and conductors 33—33 lead 50 from the brushes through posts 34—34 to a switch 35 on the stick 26. When the switch is closed it causes an increase in the current flow and a consequent increase in the magnetic pull between the armature and the field. This in- 55

crease is sufficient to rotate the casing 30 against the action of a coil spring 36 whose ends are respectively attached to the casing 30 and to the housing 5. The rotational displacement of the casing is limited by cooperating stops 37-38 on the casing and housing.

The upper portion of the casing 30 is provided with a cam 39 (Figs. 3-5) adapted to project through an aperture 40 in the housing 5. A pair of spaced rollers 41-41 are carried in a depending portion 42 of the sear plunger 19 and are disposed in the plane of the cam 39. Upon rotation of the casing 30 by closing the electric circuit, 10 the cam 39 engages the nearest roller and retracts the sear plunger from engagement with the cam follower. The point of the cam comes to rest between the rollers 41 and securely holds the sear plunger in retracted position as shown in 15 Fig. 3. The second roller serves in the nature of a stop to supplement or replace the stop 37. When the electric circuit is opened the coil spring 36 restores the casing 30 to the normal position shown in Figs. 2 and 4 and the sear plunger is urged by its spring 23 into engagement with the cam follower.

The trigger motor unit B, which forms the subject of a separate application includes a spring 30 43 which is generally common to this type of mechanism as seen by my prior patent No. 1,770,125 of July 8, 1930. This spring acts on a slide 44 which receives the impulse transmitted by the cable 15 and the spring serves to restore 35 the slide when the cam follower is not acted on by the cam 10. When the cam follower is depressed by the cam 10 the cable retracts the slide 44 and compresses the spring 43.

In the modification shown in Fig. 7 the field 40 casing 45 carries a pinion 46 meshing with a rack 47 on the sear 48.

I claim:

1. In a synchronizing mechanism, an impulse generator including a housing, a driven cam 45 shaft extending into the housing, a cam follower mounted in the housing, a sear plunger engageable with the cam follower to hold it immovable, a spring normally holding the sear plunger into engagement with the cam follower, 50 an armature on the cam shaft, a casing rotatable about the axis of the cam shaft, a magnetic field on the casing, an electrical circuit between the armature and casing and including a switch, a spring for rotating the casing, means for limiting movement of the casing, and a cam on the casing engageable with the sear plunger to disengage it from the cam follower.

2. In a synchronizing mechanism, an impulse generator including a housing, a driven cam 60 shaft extending into the housing, a cam follower mounted in the housing, a sear plunger engageable with the cam follower to hold it immovable, an armature on the cam shaft, a casing rotatable about the axis of the cam shaft, a magnetic field 65 on the casing, an electrical circuit between the armature and casing and including a switch, a spring for rotating the casing, means for limiting movement of the casing, and means on the casing and engageable with the sear plunger to recipro- 70 cate the same.

3. In a synchronizing mechanism, an impulse generator including a housing, a driven cam shaft extending into the housing, a cam follower mounted in the housing, a sear plunger engageable with the cam follower to hold it immovable, a spring normally holding the sear plunger in engagement with the follower, an electrical unit within the housing including a rotatable field member, a spring for said member, and means on said member engageable with the sear plunger to disengage it from the cam follower. 5

4. In a synchronizing mechanism, an impulse generator including a housing, a driven cam shaft extending into the housing, a cam follower mounted in the housing, a sear plunger engageable with the cam follower to hold it immovable, an electrical unit within the housing including a rotatable field member, a spring for said member, and means on said member engageable with the sear plunger to disengage it from the cam follower. 10

5. In a synchronizing mechanism, an impulse generator including a housing, a driven cam shaft extending into the housing, a cam follower mounted in the housing, a sear plunger engageable with the cam follower to hold it immovable, an electrical unit within the housing including a rotatable field member, a spring for said member, and means on said member engageable with the sear plunger to reciprocate the same. 25

6. In a synchronizing mechanism, a driven cam shaft, a cam follower, a sear engageable with the cam follower to hold it immovable, an electrical unit including an armature driven by the cam shaft and a rotatably mounted field, a spring for counter-rotating the field, and means on said field engageable with the sear to disengage it from the cam follower. 35

7. In a synchronizing mechanism, a driven cam shaft, a cam follower, a sear engageable with the cam follower to hold it immovable, an electrical unit including an armature driven by the cam shaft and a rotatably mounted field, a spring for counter-rotating the field, and means on said field engageable with the sear to reciprocate the 40 sear. 45

8. In a synchronizing mechanism the combination with a driven cam shaft, a cam follower, and a sear engageable with the cam follower to hold it immovable, of an electrical unit including a rotatably mounted field, means for counter-rotating the field, and means on said field engageable with the sear to disengage it from the cam follower. 50

9. In a synchronizing mechanism the combination with a driven cam shaft, a cam follower, and a sear engageable with the cam follower to hold it immovable, of an electrical unit including a rotatably mounted field, means for counter-rotating the field, and means on said field engageable with the sear to reciprocate the sear. 55

10. In a synchronizing mechanism, a housing, an impulse generator including a follower mounted in the housing, a sear plunger movable transversely of the housing, and engageable with the 60 follower to hold it immovable, and an electrical unit within the housing and including a rotatable member coaxial with the generator for disengaging the sear plunger from the follower. 65
